UNITED STATES PATENT OFFICE.

CHRISTOPHER C. BOYKIN, OF NORFOLK, VIRGINIA, ASSIGNOR OF ONE-FOURTH TO JOHN W. STEEL AND HERBERT S. HAZLETTE, OF SAME PLACE.

LETTER-FILE.

SPECIFICATION forming part of Letters Patent No. 606,508, dated June 28, 1898.

Application filed April 23, 1897. Serial No. 633,477. (No model.)

To all whom it may concern:

Be it known that I, CHRISTOPHER C. BOYKIN, a citizen of the United States, residing at Norfolk, in the county of Norfolk and State 5 of Virginia, have invented a new and useful Letter-File, of which the following is a specification.

The invention relates to improvements in letter-files.

10 The object of the present invention is to improve the construction of letter-files and to provide a simple, inexpensive, and efficient one capable of readily perforating a letter or other paper preparatory to filing it.

15 Another object of the invention is to prevent the cutters which perforate the paper from becoming clogged with the cut-out portions and to cause such severed pieces to fall readily from the device.

20 The invention consists in the construction and novel combination and arrangement of parts, as hereinafter fully described, illustrated in the drawings, and pointed out in the claim hereto appended.

25 In the drawings, Figure 1 is a perspective view of a letter-file constructed in accordance with this invention, the hinged filing-rods being swung away from the rigid ones. Fig. 2 is a longitudinal sectional view, the filing-rods being interlocked. Fig. 3 is a transverse sectional view showing the spring engaging the hinged filing-rods. Fig. 4 is a detail perspective view of the base-plate. Fig. 5 is a detail sectional view of the cutting device.

30 Like numerals of reference designate corresponding parts in all the figures of the drawings.

1 designates a base-plate secured by screws or other suitable fastening devices to a supporting-board 2 at one end thereof and having a perforation located beyond the board to form a hanger in order that the letter-file may be readily suspended from a nail or other suitable support when it is not in use. The base-plate, which is provided with a central opening 3, has bearing-recesses 4 at opposite sides thereof, which receive the ends of a transverse enlargement or rib 6 of a cutting-lever 7, whereby the latter is fulcrumed on the base-plate. The bearing-recesses 4 are located ad-

jacent to one end of the opening 3, and the end portions or pintles of the transverse rib 6 are rounded to fit the bearing-recesses.

The engaging end of the cutting-lever is extended laterally at each side and is provided with depending cutters 8, while the other end, which forms the hinged portion of the lever, is provided with a raised or angularly-disposed lip 9. The lip 9 is engaged by a coiled spring 10, and when it is arranged flat against the adjacent portion of the base the engaging portion of the lever is held elevated in position preparatory to cutting a letter or other paper, so that it may be readily strung on filing-wires 11 and 12. The coiled spring which holds the engaging portion of the lever normally elevated is mounted on a fastening device 13, such as a bolt or screw, which is connected with the base-plate 1 at the adjacent end of the opening 3.

70 The cutters 8, which are provided with V-shaped notches and which consist of a rod or core and a cutting-tube, are constructed substantially the same as those shown and described in Letters Patent No. 550,435, granted to me November 26, 1895.

75 The base-plate and the board 2 are provided with registering perforations 14 and 15, located beneath each cutter, and each perforation is tapered and gradually increases in diameter from its top to its bottom. These tapering perforations facilitate the discharge of the cut-out portions of the paper and the V-shaped notches of the cutters cause the cut-out portions of the paper to be creased or bent 80 during the cutting operation, whereby when they are completely severed from the body portion of the paper they will be caused to spring out of the V-shaped notches and automatically free the cutters. The raised portion or engaging end of the cutting-lever is depressed against the action of the spring, which immediately returns the cutting-lever to its initial position after the hand is removed from it, and the body portion of the 85 paper is prevented from being carried upward by the cutters, as it is arranged beneath a metal plate 16. The metal plate 16, which is provided with perforations to register with the tapering perforations, is mounted in a 90

95 100

recessed or reduced portion of the base-plate, and it has its outer edge bent upward to form a flaring mouth to enable the letter or other paper to be cut to be readily introduced beneath it.

The filing-wires 11 are rigidly mounted on the base-plate at one end thereof, while the other filing-wires 12, which are connected by a transverse portion 17, are hinged to the base-plate and extend through slots of the same and have their upper ends curved in the direction of the rigid filing-wires 11. The transverse portion 17 of the hinged filing-wires extends beneath the base-plate and is engaged by the ends of a flat spring 18, which is adapted to hold the hinged wires at any adjustment. The flat spring 18 is centrally secured to the board 2, and its ends bear against the transverse portion 17 of the filing-wires near the ends of the same, as clearly illustrated in Fig. 2 of the accompanying drawings.

The upper ends of the filing-wires are beveled and provided at their inner faces with recesses 19, forming shoulders which are interlocked when the parts are arranged as illustrated in Fig. 2 of the accompanying drawings. The resiliency of the hinged filing-wires is sufficient to hold the shoulders firmly interlocked, and when it is desired to disengage them the hinged filing wires or rods are compressed or forced toward each other. The beveled faces of the engaging ends of the

filings wires or rods are adapted to engage each other automatically when the hinged wires or rods are forced against the rigid ones.

It will be seen that the bill-file is exceedingly simple and inexpensive in construction, that it is strong and durable, and that it will enable a letter or other paper to be quickly perforated and strung on the filing-wires. It will also be apparent that the cutter is automatically returned to its initial position and that the severed portions of the paper are automatically discharged from the cutters.

45

What I claim is—

In a letter-file, the combination of a base provided at opposite sides in its upper face with bearing-recesses, a cutting-lever provided between its ends with lugs forming pin-tles and resting in the bearing-recesses, a fastening device extending through the lever and projecting above the same, and a coiled spring disposed on the fastening device and bearing against the upper face of the lever to hold its cutting end normally elevated, said fastening device serving to support the spring and to secure the lever to the base, substantially as described.

In testimony that I claim the foregoing as my own I have hereto affixed my signature in the presence of two witnesses.

CHRISTOPHER C. BOYKIN.
